(No Model.)

J. M. BAILEY.
FUEL GAS APPARATUS.

No. 478,549.

Patented July 12, 1892.

UNITED STATES PATENT OFFICE.

JOHN M. BAILEY, OF BRISTOL, VIRGINIA.

FUEL-GAS APPARATUS.

SPECIFICATION forming part of Letters Patent No. 478,549, dated July 12, 1892.

Application filed February 14, 1891. Serial No. 381,487. (No model.)

To all whom it may concern:

Be it known that I, JOHN M. BAILEY, of the city of Bristol, county of Washington, and State of Virginia, have invented certain new and useful Improvements in Fuel-Gas Apparatus, which improvements are fully set forth in the following specification and in the accompanying drawings.

The invention relates to the production of a cheap and convenient fuel-gas from crude petroleum-oil for the purpose of generating steam and for use in furnaces, smelting-works, forges, and for heating offices, dwelling-houses, and buildings of all kinds.

15 In the accompanying drawings, which form a part of my specification, Figure 1 is a partly-sectional and partly a side elevation of the apparatus employed in carrying out my invention. Fig. 2 is a plan view of one of the 20 diaphragms. Fig. 3 is a portion of one of the diaphragms in perspective.

In describing the apparatus reference is made to the drawings and the letters of reference marked thereon.

25 A represents a cylinder or vessel.

B B represent a pipe extending from an air-pump to the bottom of the cylinder or vessel.

C C are diaphragms.

Fig. 2 shows the diaphragm and the position of the rows of projections I I.

30 W L is the line to which the cylinder is filled with hydrocarbon oil.

G is broken stone, gravel, shells, metallic scrap, or other loose analogous non-absorbent material, which is submerged in the oil and which fills the spaces between the diaphragms, whose use is to divide the bubbles of air, causing more intimate contact and greater friction between the atoms of air and the atoms 35 of oil.

40 H is a hot-air chamber heated by the exhaust-steam and, if necessary, by other steam-pipes, from which the air at the desired temperature is drawn and pumped into the carbureting cylinder or vessel A.

45 I I are upright pieces attached to the diaphragms, placed in rows across the plane of the diaphragms, so arranged that the spaces in one row are opposite the center of the 50 upright pieces in the succeeding row, which causes the air as it passes between them from one side of the cylinder to the other to pur-

sue a zigzag course, as shown by the dotted arrows in Fig. 2. The diaphragms are placed one on top of another in the cylinder or vessel, the protuberances I I and the non-absorbent material G keeping them the proper distance apart. They fit the cylinder closely, but are not attached to it and are not constructed to hold oil.

55 The air when forced into the bottom of the cylinder or vessel through the pipe B follows the course of the dotted arrows in said pipe, passes to the right of the cylinder or vessel, rises through the aperture K, passing through 60 the oil and interstices formed by the broken stone or other loose material in an irregular zigzag course, between the lower diaphragm and the one immediately above it, and through the material G to the opposite side of the cylinder or vessel, where it rises through the aperture K at the second diaphragm, and so on 65 from side to side of the cylinder or vessel, pursuing a perpendicular and an irregular horizontal zigzag course through the broken stone or 70 other loose analogous material until it emerges 75 in the space above the upper diaphragm, from which it passes through the pipe F to a suitable holder. In pursuing the above-described course the air travels a great distance, 80 and by means of the friction produced by being forced through the interstices between the broken stone or other loose non-absorbent material the particles of air become impregnated with the oil, so that a combination is 85 formed, and the result is a so-called "fixed gas," or sufficiently permanent for all practical purposes, and which will not condense under ordinary temperatures, is highly inflammable, and produces when ignited an intense 90 heat.

Having thus described my invention, what I claim is—

1. A fuel-gas apparatus consisting of a cylinder or vessel filled nearly to the top with 95 loose broken stone or analogous granular non-absorbent material and crude oil, the oil submerging the non-absorbent material, an air-inlet pipe at or near the bottom of said cylinder, and carbureted-air-exit pipe at or near 100 the top of said vessel, all substantially as described.

2. In a fuel-gas apparatus, the combination, with a cylinder or vessel filled nearly to the

top with loose broken stone or other analogous non-absorbent material and crude oil, the oil submerging the non-absorbent material, of a series of loose diaphragms horizontally disposed one above the other and separated a few inches from each other, forming a series of chambers for said non-absorbent material, each of said diaphragms having an aperture on one side and arranged in said cylinder or vessel, whereby the aperture of each alternating diaphragm shall be on the opposite side of the cylinder or vessel from that of the pre-

ceding one, an air-inlet pipe at or near the bottom of the cylinder or vessel, and a carbureted-air-exit pipe at or near the top of said cylinder or vessel, all substantially as described.

In testimony whereof I affix my signature in the presence of two witnesses.

JOHN M. BAILEY.

Witnesses:

W. M. TEHAN,
H. H. SHEEN.
